RUBBER SEALED FASTENER

Filed Nov. 22, 1929

INVENTOR,
Samuel H. Norton,
BY R. S. Kelley,
ATTORNEY.

UNITED STATES PATENT OFFICE

SAMUEL H. NORTON, OF MEADVILLE, PENNSYLVANIA, ASSIGNOR TO HOOKLESS
FASTENER COMPANY, A CORPORATION OF PENNSYLVANIA

RUBBER SEALED FASTENER

Application filed November 22, 1929. Serial No. 409,014.

My invention relates to fastening devices and particularly to means for covering and sealing a fastening device of the type having multiple fastener elements attached to flexible stringers.

5 One of the objects of my invention is to provide an improved fastening device of this type having means for covering at least one side of the fastener elements.

10 Another object is to provide an improved fastener of the above type having improved means for sealing the fastener when closed.

Still another object is to provide improved sealing and covering means for a slide fastener attached directly to the fastener stringers so as to leave portions of the stringers projecting beyond the covering means for connecting the fastener to an article to be fastened.

20 A further object is to provide a bag such as a dust receptacle for vacuum sweepers with improved fastening means for closing the slit in the bag which has means for sealing the fastener.

25 A more specific object is to provide an improved slide fastener having strips of rubber or similar material attached directly to the fabric stringers of the fastener and overlying the fastener elements.

30 Other objects and advantages of my invention will more fully appear during the course of the following specification.

In the accompanying drawing I have shown for purposes of illustration three embodiments which my invention may assume in practice. In this drawing:

35 Fig. 1 is a perspective view illustrating a portion of a vacuum sweeper in which the fastening means of my invention may be incorporated.

40 Fig. 2 is a face view of a portion of the vacuum sweeper bag illustrating the fastening device on an enlarged scale.

Fig. 3 is a transverse sectional view on line 45 3—3 of Fig. 2.

Fig. 4 is a perspective view of a portion of the fastener covering means of my invention.

50 Fig. 5 is a fragmentary perspective view illustrating the method of attaching my improved fastening means to an article.

Fig. 6 is a transverse sectional view similar to Fig. 3 showing a modified form of my invention.

Fig. 7 is a similar sectional view illustrating a still further modification.

The vacuum sweeper illustrated in Fig. 1 is of a familiar type having a motor and fan portion 8, a handle 9 and a dust receiving bag 10. Such bags must be provided with an opening for removal of the dust from the bag and the fastening means of my invention may be utilized to close such opening.

A slide fastener is preferably employed, the one illustrated being of the same general type as disclosed in the patent of Gideon Sundback No. 1,219,881, March 20, 1917. The fastener illustrated comprises a pair of flexible stringers in the form of fabric tapes 12 and 13 which are attached to the opposite edges of an opening to be closed. In the present instance each of the tapes is attached to the material 14 of the vacuum sweeper bag by stitching 15 as indicated in Fig. 5. To the adjacent edges of these stringers are attached rows of cooperating fastener elements 16 in a manner well known in the art. It will be noted that there is a slight space between the end of each of the fastener elements and the corded edge of the tape so that the opening is not completely sealed, one of these spaces being designated 17 in the drawing. The fastener elements are opened and closed by means of a slider 18 operated by a pull 19 along the fastener elements.

The fastener covering means of my invention as applied to a vacuum cleaner, functions mainly to seal completely the opening but it will be understood that in other applications there will be other advantages derived such as improving the appearance of the article. In the illustrated embodiment my improved fastener covering means comprises a pair of covering strips 20 and 21 which are integrally united at the lower end by the portion 22 and may, if desired, be united also at the upper end. These covering strips are preferably made of molded rubber having suitable characteristics for the purpose and the recesses 23 and 24 are formed in the molding operation, which recesses pro-

vide a suitable space for the fastener elements and for the travel of the slider 18. A pair of flexible flaps 25 and 26 extend along the meeting edges of the covering strips and it will be readily seen that these flaps provide a very efficient sealing means especially when pressure is built up on their opposite faces as in a vacuum cleaner bag. It will, of course, be understood that these flaps may be dispensed with where an extremely efficient sealing means is not desired. The covering strips as stated before, are preferably made from molded rubber which can be secured to the fabric tapes at points spaced from the other edges of the same by a suitable rubber cement or a vulcanizing operation. By attaching the strips so as to allow the tape to extend beyond them and having the covering means wholly carried by the stringers, a unitary fastening device is obtained which may be attached directly to any article to be fastened.

Instead of cementing or vulcanizing the covering strips to the fastener stringers they may be provided with extensions 27 and 28 which are secured to the stringers by stitching 29. This method of attaching the covering strips will be particularly desirable where the strips are formed out of some material other than rubber, such as leather or the like.

In the modified construction shown in Fig. 7 instead of the flaps 25 and 26 the meeting edges are provided with beaded portions 30 and 31 which have cooperating rounded surfaces meeting in a line contact. This construction may be especially desirable in applications other than the vacuum sweeper bag, such as rubber overshoes where it is desired to keep water from going through the fastener.

In operation, with the forms illustrated in Figs. 3 and 6, assuming that the fastener is closed and the vacuum cleaner is operating, pressure will be built up in the bag 10 and act on the flaps 25 and 26 pressing them together and causing a substantially airtight seal. When the fastener is opened by operation of the slider in the proper direction, the stringers may be separated in the usual manner and the covering strips will not hinder in any way the opening of the fastener to provide access to the interior of the bag. In the form illustrated in Fig. 7, the resilient action of the covering strips will hold the rounded portions 30 and 31 in contact and thus provide a seal for the fastener independent of whether or not pressure is built up on its outside surfaces.

As a result of my invention it will be seen that a unitary fastening device has been provided having improved means for covering the fastener elements without hindering in any way the ability of the fastener to be at-

tached to the edges of any article to be fastened. It will also be seen that my invention provides a very effective sealing means for a slide fastener which will prevent dirt, wind or water from passing through the fastener. It will be observed that my fastener with the improved covering means can be manufactured at a low cost since all that is required is to mold a covering strip out of rubber and attach it to the fabric stringers by cementing or vulcanizing, or if desired, the strips may be sewed to the stringers as in one modification described above.

While I have in this application specifically described three embodiments which my invention may assume in practice, it will be understood that these embodiments are merely for the purposes of illustration and description and that various other forms may be devised within the scope of my invention as defined in the appended claims.

What I claim as my inventions is:

1. The combination with a fastening device of the type having a pair of flexible stringers and cooperating fastening means on the adjacent edges of said stringers, of covering strips wholly carried by said stringers and permanently connected thereto at points spaced from the outer edges of said stringers, said covering strips having portions overlying said fastening means, said fastening device and attached covering strips constituting a separate and distinct unit adapted to be connected to the separable edges of an article to be fastened.

2. The combination with a fastening device of the type having a pair of flexible stringers and cooperating fastener elements on the adjacent edges of said stringers, of a pair of covering strips extending along the adjacent edges of said stringers and permanently connected thereto adjacent the fastener elements so as to leave a portion of each stringer projecting beyond the covering strips for attachment to an article to be fastened, said covering strips overlying said fastener elements and contacting with each other to provide a complete covering for said elements, said fastening device and attached covering strips constituting a separate and distinct unit adapted to be connected to the separable edges of an article to be fastened.

3. The combination with a fastening device of the type having a pair of flexible stringers and rows of fastener elements secured to the adjacent edges of the said stringers, of covering strips attached to said stringers along their adjacent edges and spaced from the outer edges of the stringers so as to leave portions of the stringers for connection to an article to be fastened independently of said strips, said strips having portions overlying said fastener elements and meeting each other along the longitudinal center line of the fastening device, said fastening device

and attached covering strips constituting a unit adapted to be connected as a unit to the separable edges of an article to be fastened.

5. 4. The combination with a fastening device of the type having a pair of flexible stringers and cooperating fastener elements secured to the adjacent edges of said stringers, of means for sealing said fastening device to prevent 10 water and air from passing therethrough comprising a pair of covering strips made of flexible material and wholly carried by said stringers adjacent said fastener elements and overlying said elements, said covering strips 15 being in contact with each other when the fastener is closed and being formed to provide a substantially leak-proof joint, said fastening device and attached covering strips constituting a separate and distinct unit 20 adapted to be connected to the separable edges of an article to be fastened.

5. The combination with a fastening device of the type having a pair of flexible stringers and cooperating fastener elements secured 25 to the adjacent edges of said fastener stringers, of a pair of covering strips secured to said stringers and spaced from the outer edges thereof to leave portions of the stringers for connection to an article to be fastened, said strips having free portions overlying the fastener elements, and a pair of 30 flexible flaps carried by the adjacent edges of such portions adapted to lie against each other and provide a substantially leak-proof 35 joint between them.

6. A unitary fastening device for attachment to the edges of an opening comprising a pair of fabric stringers, rows of cooperating fastener elements on the adjacent edges 40 of said stringers, a slider movable along said elements to engage and disengage the same, and covering means mounted on one side of said stringers comprising strips of flexible material secured directly to and wholly carried by said fabric stringers and having portions overlying the fastener elements, said 45 flexible strips being integrally united at one end, said fastening device and attached covering strips constituting a separate and distinct unit adapted to be connected to the 50 separable edges of an article to be fastened.

7. A unitary fastening device adapted for attachment to the edges of an opening to be 55 fastened comprising a pair of flexible stringers each having a row of fastener elements mounted thereon, and rubber covering strips secured to the fabric stringers adjacent said fastener elements but spaced from the outer 60 edges of the stringers to leave portions for attachment to the edges of said opening, said covering strips extending over the fastener elements and substantially completely covering one side of the same, said fastening device and attached covering strips being adapt- 65

be secured to the edges of an opening to be fastened comprising a pair of fabric stringers having rows of cooperating fastener elements on their adjacent edges, and means carried by the stringers for covering one side of said fastener elements and substantially sealing the fastener when closed, comprising a pair of rubber strips vulcanized to the fabric stringers along their adjacent edges and spaced from the outer edges of the stringers, said rubber strips overlying the fastener elements and meeting each other along the longitudinal center line of the fastener.

9. The combination with a fastening device of the type having a pair of fabric stringers, rows of cooperating fastener elements at their adjacent edges and a slider movable along 85 said elements to control the same and rubber covering strips each having one longitudinal edge secured to said fabric stringers outside the fastener elements but spaced from the outer edges of the stringers, said strips having their ends adapted to overlie the fastener elements and meeting each other along the longitudinal center line of the fastener, the adjacent portions of said strips being recessed to provide space to allow the slider 95 to operate between the fastener elements and said strips.

In testimony whereof I affix my signature.

SAMUEL H. NORTON.
